UNITED STATES PATENT OFFICE.

GEORGE W. KORN, OF CHICAGO, ILLINOIS.

DESIGN FOR A KNIFE-HANDLE.

SPECIFICATION forming part of Design No. 21,867, dated September 27, 1892.

Application filed February 26, 1891. Serial No. 383,019. Term of patent 7 years. Patented in Germany October 13, 1890, No. 907.

To all whom it may concern:

Be it known that I, GEORGE W. KORN, a citizen of the United States, residing in Chicago, in the county of Cook and State of Illinois, have invented and produced a new and original Design for Knife-Handles, (the same having been patented in Germany by Letters Patent No. 907, dated October 13, 1890,) of which the following is a specification.

10 Figure 1 is an elevation of one side of my knife-case, and Fig. 2 a like view of the opposite or reverse side of the case.

15 The leading feature of the design consists in the handle having an outline substantially such as that hereinafter described.

20 In the drawings, A represents one side of the knife-case, and B the other side. Both are given an outline in the similitude of a mug or similar drinking-vessel, the part C 25 representing the handle of the mug, and one end of the case being rounded or tapered, as shown, to resemble the cap or cover of the mug, and the other end being fashioned in resemblance to the base or bottom of the mug.

25 The sides A and B are each ornamented, the one with the head of a king *d*, carved or molded, in relief, in a niche-like space formed by col-

umns *e* and arch *f* and a couple of cherubs carrying a barrel between them on long poles similarly carved or molded, as shown at *g*. 30 The other side is provided with a head, in relief, of a queen *h* in a similar niche-like space, and with a representation of two cherubs carrying a load of fruit upon a pole mounted on their shoulders, as shown at *i*. The part C 35 may be surfaced with a rustic design and the sides A and B be provided with cross-bars *j* and *k*.

What I claim is—

1. The design for a knife case or handle, 40 substantially as herein described and shown.

2. In a design for a knife case or handle, the side A, having an outline in the similitude of a mug and ornamented, substantially as herein described and shown. 45

3. In a design for a knife case or handle, the side B, having an outline in the similitude of a mug and ornamented, substantially as herein described and shown.

GEORGE W. KORN.
